UNITED STATES PATENT OFFICE.

HARRY RANDOLPH VAN DEVENTER, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

TRIPPING MECHANISM FOR IGNITERS.

1,190,823.

Specification of Letters Patent.

Patented July 11, 1916.

Application filed January 15, 1915. Serial No. 2,497.

To all whom it may concern:

Be it known that I, HARRY RANDOLPH VAN DEVENTER, a citizen of the United States, residing at Sumter, in the county of Sumter 5 and State of South Carolina, have invented certain new and useful Improvements in Tripping Mechanism for Igniters, of which the following is a specification, reference being had to the accompanying drawing.

10 My invention relates to ignition mechanism for internal combustion engines and more particularly to a mechanism using an oscillating magneto in conjunction with a make-and-break contact interrupter.

15 The object of my invention is to provide in such mechanism, a novel arrangement of parts whereby the same may be operated to effect ignition of a charge after the engine has been moved into the power stroke as is 20 desirable in starting.

Another object is to so arrange the parts that after having been adjusted for starting and the initial power stroke is made, the starting adjustment is automatically 25 thrown out and replaced by the running adjustment.

Various other novel features of the invention will be apparent from a perusal of the accompanying specification and drawings.

30 My invention is illustrated in the accompanying drawings, in which—

Figure 1 shows a front elevation, with the magneto removed and the engine body shown in fragmentary portions. Fig. 2 is a side 35 elevation of the mechanism removed from the engine and with the driving means omitted for the sake of clarity.

Referring to the drawings in detail, 35 is the engine body on which are mounted the 40 various parts of the apparatus constituting my invention. The igniter unit is mounted on that portion of the engine body constituting the cylinder wall and consists of a main frame body 3 adapted to be mounted 45 on the cylinder wall, by means of the bolts 46 and 47, with the igniter body 28 extending therefrom into the ignition chamber of the engine. This main frame body 3 also carries an outwardly projecting bracket 22 50 on which the magneto 23 is mounted. Other projections in the form of anchor posts 33 and 34 extend outwardly from the frame 3 to serve as anchorages for the operating springs 36 and 37 respectively, which springs

are omitted from Fig. 2 in order to give a 55 clearer view of other elements of the mechanism. The igniter body 28 carries on its inner face an electrode 27 constituting the fixed electrode of the igniter contacts, the electrode 27 being insulated from the igniter 60 body but having electrical connection with the binding post 37 mounted on the outer face of the frame 3. The igniter body 28 also carries the igniter operating shaft 2 which is journaled therein and extends 65 therein and extends therethrough, terminating at the inner end in movable electrode 26 of the igniter contacts, and projecting at the outer end beyond the outer surface of the frame 3. On this outer portion the shaft 2 70 carries an operating lever 31 fixed thereto and farther beyond this a trip lever 1 journaled on the end of the shaft. The operating lever 31 and shaft 2 are held normally in a given position relative to the frame by 75 means of a torsion spring 38 connected between the lever 31 and the frame, while the trip lever 1 is held normally in a given position relative to the frame by means of the pull springs 36 and 37, each connected 80 through roller bearings, at one end to one end of the trip lever 1 and at the other to one of the anchor posts 33 and 34 respectively.

Motion is transmitted from the trip lever 85 1 to the operating lever 31 by means of a stud 29 which constitutes an enlarged extension of the spindle 7, the stud 29 acting on the lever 31 through an adjustable tappet consisting of the screw and locknut adjustment 32. The magneto 23 is mounted on the bracket 22 with its operating shaft in alignment with the magneto operating shaft 2 and the magneto shaft coupled with the trip lever through the crank 20 and pin 21 carried by 95 the magneto shaft, and the bifurcated finger 30 carried by the trip lever extending downwardly therefrom and straddling pin 21. Connections for the ignition circuit are made from the magneto windings through the 100 magneto binding post 25, conductor 24, igniter binding post 49, igniter electrode 27, movable igniter electrode 26 and back to the magneto winding through the frame or ground.

For the purpose of partially cocking the trip lever a hand lever 4 is pivoted on the outer reduced portion of the anchor post 33

and extends into operative engagement with the outer reduced portion of the spindle 7. The distance between the axis of rotation of the lever 4 and its lower end, where it engages the spindle 7, is such that when the handle of the lever is rotated upward, as indicated by the arrow 5, the end of the lever will engage the spindle 7 and push it down rotating the trip lever through the angle $b-d$ which moves the trip finger 9, carried by the trip lever, from the line $a-b$ into the line $c-d$, at which point the spindle 7 rests in the depression 8 of the lever 4 and the lever 4 and trip lever is held against further rotation by the nose 6 on the lever 4. It is desirable when not in use that the lever 4 be held away from the spindle 7 and other moving parts and to accomplish this the handle of the lever is weighted so as to normally tend to fall into the line $g-h$ and raise the lever clear of the working parts.

For operating the trip lever advantage is taken of the movement of the exhaust rod indicated at 10 (see Fig. 1) and as its general function of opening the exhaust valve during a portion of the cycle of the engine is well known in the art and forms no part of the present invention, the entire arrangement for performing such function is not here shown, but only such portion as is necessary to a clear understanding of the present invention. It suffices to point out that the rod 10 is slidably mounted on the engine frame by means of the slide bearings 11 and 12 and is operated by the cam 14 through roller bearing 13 carried at the right-hand end of the rod 10. The cam 14 is connected with the engine crank through the usual two to one reducing gear so as to make one revolution in each cycle of two revolutions of the engine shaft. This cam is so shaped that the exhaust rod is given two strokes or reciprocations of different degrees in length during each cycle of the engine. For convenience I will term these strokes the long and short strokes, the long stroke operating first to effect ignition and later to open the exhaust valve in a well known manner and the short stroke operating the ignition mechanism in starting only and in a manner hereinafter set forth. The roller bearing 13 is held in engagement with the surface of the cam 14 by means of a compression spring 39 connected to it and bearing against the slide bearing 11. A depending arm 40 fixed to the rod 10 carries a push finger 15 pivoted to the arm at 41 and adapted to be adjusted in angular relation with the rod by means of an adjusting screw 42 threaded in the end of the finger 15 and bearing against an abutment 43 on the rod 10, the adjusting screw being held against the abutment under tension of a pull spring 16 extending between the lever 4 and the end of the finger 15. The free end of the push finger 15 is adapted to engage the

trip finger 9, upon movement of the rod 10 to the left, and rotate the trip lever counterclockwise until the end of the push finger moves beyond the arc scribed by the end of the trip finger. This occurs after each full or long stroke of the rod 10 while in the short stroke of the rod the push finger 15 is carried back just a little to the right of the line $c-d$ and so rests upon but does not engage the trip finger 9 when the trip lever is in the position shown in Fig. 1.

The operation of my invention is as follows: It being desired to start the engine, it is turned to the power stroke and the handle of the trip lever 4 rotated in the direction of the arrow 5 which moves the trip lever 1 in a counterclockwise direction through the angle $b-e$ and locks the same in a position with the trip finger 9 in the line $c-d$, in a manner as previously described. The ignition circuit is then enabled, and the engine turned either against compression, (in which case the cam may be considered to rotate from left to right) or in the direction of the power stroke, (when the cam may be considered to rotate from right to left). In either case the roller 13 first rides the indented portion near 17 or 19 of the cam. This permits rod 10 to travel just far enough to the right to enable the push finger 15 to drop below and engage the trip finger 9 which is held on the line $c-d$ by lever 4. As the cam continues to revolve (in either direction) rod 10 begins to move to the left as roller 13 travels up the face 17 or 19 of the cam. This outward motion of the rod 10 carries push finger 15 toward the left and trip finger 9 travels with it. This releases the lever 4, which drops out of the way, and when the trip finger reaches the angle $d-f$ push finger 15 slides over the nose of the trip finger, which is released and snaps back to normal position under the force of the pole springs 36 and 37. This operation may be termed the "short stroke" of the mechanism.

It will be remembered that the normal position of the nose of the trip finger 9 is on the line $a-b$, consequently unless the trip finger is first locked up so that the nose is on the line $c-d$, it is impossible for 15 to engage it except once per revolution of the cam 14 and only when 13 is at the lowest indented portion of 18 on the cam. But when the trip finger is locked up by means of lever 4 then finger 15 may engage the trip finger 9 when 13 is between 17 and 18, or 18 and 19 on the cam, which enables the ignition device to be operated by throwing the engine back against compression, or by turning same in the power stroke without making a full revolution. The engagement of the trip finger 9 by the push finger 15 without 9 being locked up by 4

may be termed the "long stroke" of the mechanism.

During the normal running of the engine, the cam 14 being geared at one-half engine speed, the exhaust valve and the ignition device are only operated once per revolution of the cam; and the normal operation of the engine will be readily understood by reference to the following: After 5 the engine is started the cycle is continued up to the point of the occurrence of the long stroke of the rod 10. The push finger 15, in the right-hand portion of the stroke, is moved to the right beyond the line *a*—*b* 10 where it falls into engagement with the trip finger 9 and during the left-hand portion of the stroke is moved forward to the left rotating the trip lever through the angle *b*—*f* and tripping the same to effect ignition 15 of the new full charge under maximum compression. The short stroke occurring later as the roller 13 moves over 17 or 19 on the cam will no longer affect the igniter unit, however, as the trip lever is no longer 20 held with the trip finger 9 in the line *c*—*d* 25 and the right-hand movement of the short stroke is not sufficient in extent to permit the push finger to fall down into engagement with the trip finger when the latter 30 is in the line *a*—*b* which position it is capable of assuming during the running adjustment which now obtains. Thus during 35 the running adjustment the trip lever is thrown only once in each cycle and that in the forward movement of the long stroke 40 of the rod 10, the short strokes producing no effect.

It will be seen from the foregoing that in order to start the engine all that is necessary 45 is to turn it into the power stroke, cock the trip lever in the intermediate position and enable the ignition circuit after which the device becomes automatic in its action, upon rocking the engine, to ignite 50 the initial charge in the power stroke and change over from the starting adjustment to the running adjustment.

It is further pointed out that the novel arrangement and combination of parts herein 55 shown and described makes for efficiency and economy in maintenance and results in a device in which the electrical appliances are reduced to the simplest form and the greater part of the functioning performed mechanically.

While I have herein shown and described a preferably specific form in which the invention may be embodied I desire it understood that I do not limit myself to this 60 specific form but contemplate all such modifications as fall within the scope of the appended claims. For example, the magneto, trip lever, igniter and connected parts to be actuated as herein described may be of 65 any one of the forms shown in my co-

pending applications Serial Nos. 878,196, 878,931, 878,932, 878,933 and 879,940. In using any of these forms, it is of course understood that minor modifications may be made as found necessary to adapt the 70 appliances to the present use.

Having thus described my invention, what I claim and desire to secure by Letters Patent is:—

1. In an ignition mechanism for internal combustion engines, the combination of an oscillating magneto, a make and break igniter, a trip lever for actuating said magneto and igniter, tension means tending normally to hold the trip lever in a given 75 position, actuating means operated by the engine for tripping the trip lever at a pre-determined point in the cycle of the engine and means for holding the trip lever in a position to be tripped by the said actuating 80 means at a point in the cycle other than said first mentioned predetermined point.

2. In an ignition mechanism for internal combustion engines, the combination of an oscillating magneto, a make and break 90 igniter, a trip lever for actuating said magneto and igniter, tension means tending normally to hold the trip lever in a given position, actuating means operated by the engine for tripping the trip lever at a pre-determined point in the cycle of the engine and means coöperating with the trip lever to move and hold the same against the tension of said tension means and adapted to be released at a point in the cycle of the 95 engine other than said first mentioned predetermined point.

3. In an ignition mechanism for internal combustion engines, the combination of an oscillating magneto, a make and break 105 igniter, a trip lever for actuating said magneto and igniter, tension means tending normally to hold the trip lever in a given position, means for locking the trip lever in an off normal position against the force of 110 said tension means and means operated by the engine to trip the trip lever at a given point in the cycle of operation of the engine at all times and to trip the trip lever at a point other than the aforesaid given point 115 only when the trip lever has been locked in the off normal position.

4. In an ignition mechanism for internal combustion engines, the combination of a frame adapted to be mounted on the engine 120 body, an igniter carried by the frame and projecting into the ignition chamber of the engine, a flange carried by the frame, anchor posts carried by the frame, an operating shaft for the igniter, a magneto mounted on 125 the flange with its operating shaft substantially in alinement with said igniter operating shaft, a trip lever, tension means tending normally to hold the trip lever in a given position relative to the frame, an oscil- 130

lating rod operated by the engine to make long and short oscillations, means carried by the rod adapted normally to operate said trip lever upon a long oscillation of the rod only and means for temporarily rendering said trip lever operable by said rod carried means upon a short oscillation of the said rod.

5. In an ignition mechanism for internal combustion engines, the combination of a frame adapted to be mounted on the engine body, an igniter carried by the frame and projecting into the ignition chamber of the engine, a flange carried by the frame projecting outwardly from the engine body, anchor posts carried by the frame and projecting outwardly from the engine body, an operating shaft for the igniter, a magneto mounted on the said flange with its operating shaft substantially in alinement with said igniter operating shaft, a trip lever mounted to rotate on an axis substantially concentric with said operating shafts, pull springs connecting the trip lever with the anchor posts and tending normally to hold the trip lever in a given position relative to the frame, means coöoperating with the trip lever to move the same out of said given position against the force of the pull springs 30 into a second given position and locking it against movement by said pull springs, and a push rod operated by the engine to make alternate long and short strokes, said long and short strokes being so proportioned and 35 the path of the push rod so positioned in relation to the said given positions of the trip lever that the push rod will always engage the trip lever in the long stroke and will engage the trip lever in the short stroke 40 only when said trip lever is in the said second given position.

6. In an ignition mechanism for internal

combustion engines, the combination of a frame adapted to be mounted on the engine body, an igniter carried by the frame and projecting into the ignition chamber of the engine, a flange carried by the frame projecting outwardly from the engine body, anchor posts carried by the frame and projecting outwardly from the engine body, an operating shaft for the igniter, a magneto mounted on the said flange with its operating shaft substantially in alinement with said igniter operating shaft, a trip lever mounted to rotate on an axis substantially concentric with said operating shafts, pull springs connecting the trip lever with the anchor posts and tending normally to hold the trip lever in a given position relative to the frame, means coöoperating with the trip lever to move the same out of said given position against the force of the pull springs into a second given position and locking it against movement by said pull springs, a push rod operated by the engine to make alternate long and short strokes, said long and short strokes being so proportioned and the path of the push rod so positioned in relation to the said given positions of the trip lever that the push rod will always engage the trip lever in the long stroke and will engage the trip lever in the short stroke only when said trip lever is in the said second given position, and means for disabling the said trip lever holding means upon movement of the trip lever out of the second given position.

In testimony whereof I hereunto affix my signature in the presence of two witnesses.

HARRY RANDOLPH VAN DEVENTER.
